UNITED STATES PATENT OFFICE.

LOUVERN G. LANGE, OF PASSAIC, NEW JERSEY.

APPARATUS FOR INSERTING INSULATING DISKS IN METAL CAPS.

Application filed January 27, 1925. Serial No. 5,151.

It is common practice to provide bottles, jars, and like containers, with metal caps to serve in place of corks or stoppers, and it is also common practice to line those caps with varnished paper disks to prevent the contents of the container from coming in contact with the metal of the cap. The present practice is to punch or cut the insulating disks from a flat sheet of stock and then insert them by hand in the metal caps.

It is an object of the present invention to provide a method and machine whereby cut disks of varnished paper, or of cork, or of similar insulating material, can be inserted automatically into the metal caps in which the disks are to be used to insulate the cap from the container on which the cap is ultimately affixed.

Further objects and advantages of the present invention will be made clear by the following detailed description, and by the accompanying drawings, wherein

Fig. 1 is a plan view of the machine;

Fig. 2 is a side elevation with certain parts in section;

Fig. 3 shows in elevation the cam mechanism for advancing the caps through the machine together with certain related elements;

Fig. 4 is a detail of the intermittent driving gear, and

Fig. 5 is a sectional view of a typical finished cap.

The machine comprises a base 1 with five rigidly mounted posts or pedestals 2, 3, 4, 5 and 6. Mounted on posts 2 and 3 is a plate 7 (Fig. 1) to serve as the support for a vertical cage or stack in which the insulating disks 8 are arranged for feeding into the machine. This rack or stack is adjustable to accommodate disks of various diameters, and comprises a plurality of vertical rods 9 held at their upper ends in metal sectors 10 and 11, the latter being adjustably secured to one another by a pivot 12 about which both may swing to increase or decrease the effective diameter of the space between the rods. The lower ends of the rods are similarly held in adjustable sectors 13 and 14.

Posts or pedestals 4, 5 and 6 support a triangular plate 15 (Fig. 1) on which certain of the moving elements are mounted as hereinafter described.

Power from a driving motor is transmitted to a pulley 16 mounted on a vertical

shaft 17, the lower end of which fits in a step-bearing on plate 1, and the upper-end of which is supported and guided by a horizontal plate 18 (Fig. 2). Rigidly mounted on shaft 17 is a pinion 19 meshing with a gear 20 on a vertical shaft 21. The upper face of gear 20 carries four cams positioned 90° apart and adapted to engage with the roller 22 pivoted in the lower end of a push bar 23. This bar is adjustable in length and is free to slide through plates 18 and 15. At the upper end of bar 23 is a ball and socket connection 24 with a rocker arm 25 pivotally supported on a bracket 26 bolted to plate 15. The other end of the rocker arm engages the rod 27 of a piston 28, the function of which is to push an insulating disk down into a metal cap and there seat it squarely on the metal face as hereinafter described more at length.

A compression spring 29 co-acting between plate 15 and a collar 30 pinned to rod 27 normally holds the piston in its upper or retracted position and normally holds roller 22 in position to be engaged by the cams on gear 20.

The driving shaft 17 also carries a pinion 31, but this pinion as shown in Fig. 4 has certain of the teeth cut away so that an intermittent movement is transmitted to the gear 32 with which the pinion meshes, as will be readily understood by those skilled in the art. Gear 32 is rigidly mounted on a vertical shaft 33 supported at its lower end in a step bearing on plate 1 and passing freely through plate 18. Clamped to shaft 33 is a cam plate 34 having four radial arms 35 (Fig. 3) for use in advancing the metal caps through the machine.

By reference to Fig. 3 it will be seen that the empty metal caps enter the machine through a guideway 36, the side walls of which are adjustable toward or from one another to accommodate the machine to caps of differing diameters. This adjustment is obtained through slotted ears 37 carried by the side rails of the guide, and each provided with a clamping screw or bolt 38. When a cap has entered the machine far enough to be engaged by one of the cam arms 35, it is swung around on the arc of a circle through a guideway 39 and ultimately comes to rest immediately beneath and in alignment with plunger 28. The intermittent movement for arms 35 is brought about through the gearing shown in Fig. 4, and

exact alignment with the plunger is insured by mechanism hereinafter described. The guideway 39, like guideway 36, is adjustable in width to accommodate various kinds of caps. This capacity for adjustment is obtained by means of ears 40 integral with the inside rail of the chute and adjustably secured by bolts 41 to the under side of a stationary frame plate 42, and by similar slotted ears 43 integral with the outside rail of the chute and adjustably bolted to a stationary frame plate 44.

After the plunger has forced an insulating disk into a metal cap positioned beneath it, the cap can be moved forward by the swinging arm 35 and ultimately kicked off into the discharge chute 45. The exact form of arms 35 is not material so long as the caps are progressively moved into position beneath the plunger and ultimately delivered from that position to a discharge chute.

The vertical shaft 33 is squared at its upper end and serves to drive a circular plate 46, the function of which is to take insulating disks from the stack and carry them around into position to be forced by plunger 28 downward into the waiting empty metal cap. To effect this result the circular plate 46 has four openings 47 positioned 90° apart and each of a diameter suitable for readily picking off the lowermost insulating disk of the stack 8. The openings in plate 46 may conveniently be of oval outline to more readily receive insulating disks from the stack, and plate 46 can be of a thickness approximating that of an insulating disk. A stationary guide plate 42 serves to keep the disks from dropping out of the holes 47 while being carried around into position beneath the plunger. This plate is provided with an opening beneath the plunger through which the disks pass into the cap (see Fig. 2). Plate 46, of course, moves with an intermittent movement suitably timed by the gears of Fig. 4 to give a pause or dwell while plunger 28 is forcing an insulating disk downward into the metal cap. A spring pressed detent 50 (Fig. 2) engages with notches 51 in plate 46 to accurately center that plate over the waiting cap. When the gears of Fig. 4 again come into effective engagement, detent 50 is forced back against the tension of its spring and rides along on the edge of the disk until the latter has travelled through an angle of 90°.

A single attendant can operate several such machines simultaneously supplying insulating disks to the stack 8 and supplying empty caps to the intake guideway 36. Plunger 28 reliably performs its function of not only pushing the insulating disk into the metal cap but of there seating it firmly against the metal. This function of forcibly seating the disk in the cap is of advantage in that it permits the use of insulating disks

larger in diameter and more snugly fitting than could effectively be used if the filling of caps were done by hand according to present practice.

I am aware that various details of the machine may be altered without departing from the spirit of my invention as defined by the appended claims.

I claim:

1. In a machine for assembling disks in metal caps, a rotary actuating shaft, a member mounted on said shaft for feeding the caps to the assembling position, a second member also mounted on said shaft and rotating unitarily with said first named member for feeding the disks to the assembling position and a plunger at the assembling position for forcing the disks into the caps.

2. A machine for assembling disks in metal caps comprising a horizontal supporting surface, a vertical actuating shaft, a member mounted on said shaft for sliding the disks successively over said surface to an assembling position, means for guiding the caps in a path beneath said surface to the assembling position, a member mounted on said shaft and rotating unitarily with said first named member for moving the caps along such path, and means located at the assembling position for forcing the disks into the caps.

3. A machine for assembling disks in metal caps comprising a horizontal surface having an opening at the assembling position, a rotary member for sliding the disks over said surface to a position over said opening, means for guiding the caps in a path beneath said surface to a position beneath said opening, a rotary member having the same axis of rotation as said first named member and rotating unitarily therewith for moving the caps to said position, and a plunger operating through said opening to force the disks into the caps.

4. A machine for assembling disks in metal caps comprising a horizontal surface having an opening at the assembling position, a rotary member for sliding the disks over said surface to said opening, a supporting surface for the caps beneath said first named surface, a rotary member for sliding the caps over their supporting surface to a position beneath said opening and means for forcing the disks through said opening into the caps, said members being mounted to rotate unitarily about a common axis and being positioned with respect to each other so that they move a cap and the corresponding disk in unison to said opening.

5. In a machine for assembling disks in metal caps, a plunger, rotatable feeding means for moving the metal caps successively into position beneath said plunger and means rotating about the same axis of rotation and at the same speed as the first named

- means for moving the disks successively into position beneath the plunger and means to actuate the plunger to force each disk into a corresponding cap.
- 5 6. In a machine for assembling disks in metal caps, a rotary actuating shaft, a member mounted on said shaft for moving the caps successively to the assembling position, a member also mounted on said shaft and 10 rotating unitarily with said first named member for moving the disks separately in a path terminating at the assembling position and means at the assembling position for forcing the disks into the caps.
- 15 7. A machine for assembling disks in metal caps comprising a horizontal supporting surface having an opening at the assembling position, a rotary member for sliding the disks separately over said surface 20 to a position over said opening, a supporting surface for the caps beneath said first named surface, a rotary member for sliding the caps separately over said supporting surface to a position beneath said opening, means for rotating both of said members unitarily about the same axis, said 25 members being correlated so that while a cap is being moved over its supporting sur-
- face there is a disk directly above it being moved over its supporting surface whereby 30 a cap and the corresponding disk will reach the assembling position at the same time, and means at the assembling position for forcing the disks through said opening into the caps.
- 35 8. A machine for assembling disks in metal caps comprising a horizontal supporting surface having an opening at the assembling position, a flat plate rotating above said surface, said plate having a series of 40 openings therein, means for holding a column of disks in contact with said plate whereby the lowermost disk is fed into one of said openings as the plate passes under the column, a supporting surface for the 45 caps located beneath said first named surface, a member adapted to move the caps over said surface to the assembling position, means for rotating said plate and said last 50 named member in unison about a common axis, and means at the assembling position for forcing each disk through the openings in said plate and said disk supporting surface into a cap.

In testimony whereof I affix my signature.
LOUVERN G. LANGE.
